SHARPENING ATTACHMENT

Robert E. Wallin, New Holland, and Allison W. Blanshine, Lititz, Pa., assignors to Sperry Rand Corporation, New Holland, Pa., a corporation of Delaware
Filed Mar. 20, 1961, Ser. No. 97,009
1 Claim. (Cl. 51—246)

The present invention relates to an improvement in sharpening attachments or devices of the type shown and described in U.S. Patent Nos. 2,735,248 and 2,788,623, assigned to the assignee of this invention.

Each of the patents mentioned shows a device having a carriage manually reciprocable over a guide track. The track is radially spaced from and extends parallel to the axis of a cylindrical rotatable cutter having knives which have to be sharpened periodically. The carriage has an adjustable tool holder which supports an abrasive sharpening element. By adjusting the tool holder to proper position and then reciprocating the carriage, the abrasive element is engageable with the cutter knives to apply a sharpening or honing action thereon. When the cutter knives are sharpened, they wear away the abrasive element and it is necessary to index the element toward the cutter to compensate for such wear. In the patents mentioned, the tool holder is indexed toward the cutter each time the carriage is returned to a starting position. The carriage is reciprocated from a starting position at one axial end of the cutter. It is moved to the opposite axial end of the cutter and then back to starting position. At the starting position, the holder for the abrasive element is indexed to compensate for the wear of the sharpening element during the prior reciprocating stroke.

A difficulty with this type of arrangement is that if the carriage is reciprocated at a constant speed, the portions of the knives at the axial end of the cutter adjacent the starting position of the carriage receive most of the sharpening action, while the portions of the knives at the other axial end of the cutter get insufficient sharpening. This results from the fact that the sharpening element has its greatest sharpening effect when it first starts out. As it wears away, the sharpening effect decreases. While the sharpening variation from one end of the cutter to the other is relatively slight, for a given reciprocation of the carriage, the result is cumulative. Every time the cutter is sharpened, one axial end thereof is sharpened a little more than the other end. In time, the trueness of the cylinder generated by the cutter knives is impaired. This occurs particularly where the cutter is of substantial axial length. The greater the length of the cutter, the greater the sharpening problem. Uneven sharpening reduces operative efficiency of the cutter.

Such problem can be minimized if the operator will move the carriage rapidly when passing over the axial portion of the cutter near the starting position of the carriage and slowly when passing over the opposite end of the cutter. However, such method requires careful attention of the operator.

A main object of this invention is to provide a sharpening attachment of the character described having improved indexing means thereon, for insuring that the knives of the cutter to be sharpened are honed as much at one axial end of the cutter as at the other end.

Another object of this invention is to provide a sharpening attachment of the character described wherein improved indexing means operates with precision and costs very little over the structure heretofore provided.

Other objects of this invention will be apparent hereinafter from the specification and from the recital in the appended claim.

In the drawings:

FIG. 1 is a longitudinal vertical section through a

2

cutter mechanism having mounted thereon a sharpening attachment constructed according to this invention, such section being taken on the line 1—1 of FIG. 2 looking in the direction of the arrows; and

FIG. 2 is a plan view of FIG. 1.

Referring now to the drawings by numerals of reference, 10 denotes a forage harvester housing having a forward inlet opening 11 and a rearward outlet opening 12. Housing 10 has a pair of laterally spaced side walls 14 and 15, and a top wall 16 having an opening 18. Rotatable in the housing 10 in the direction indicated by the arrow 19 is a cutter 20. The cutter 20 has a shaft S of substantial axial length driven from a source of power, not shown. Shaft S supports three radially outwardly extending support discs 21 axially spaced along shaft S. Discs 21 carry support castings 22 for cutter knives 24. Each of the knives 24 has a cutting edge 25, all of the knife edges being located at the same radial distance from shaft S and which on rotation of the cutter generate a cylinder.

As shown best in FIG. 1, the knives 24 are cup-shaped. They are operative to exert a throwing as well as a cutting effect on forage fed through opening 11. The cut or chopped material is discharged through the outlet 12 and through a spout 26. Spout 26 terminates at a container, not shown, which receives the material. In front of the inlet 11, a pair of feed rolls 28 and 29 are provided between which the forage to be chopped passes. Such forage may comprise hay, corn or other crop material. The rolls 28 and 29 operate to compress the crop material as well as feed it into the housing 10. The material passes over infeed plate 30 adjacent the lower portion of the opening 11. A fixed shear bar 31 is mounted adjacent the opening 11 and cooperative with the knives 24 on the cutter. As the cutter 20 operates, the knives 24 successively pass the shear bar 31 and sever the material being fed thereover. The knives extend angularly (FIG. 2) relative to the axis of shaft S, whereby they exert a shearing action as they pass the shear bar 31. The cut crop material is swept along the lower arcuate portion 32 of the housing 10 by the knives 24 and then thrown upwardly through the discharge opening 12 and spout 26. As will be noted, the portion 32 of the housing is concentric with the axis of the shaft S. Cutter 20, housing 10 and the infeed rollers 28 and 29 are all supported on a common framework including support pipe 34.

In the course of operation of the cutting mechanism, 50 the cutting knives 24 become worn. Periodically, the knives must be sharpened to maintain a good cutting and throwing action with a minimum of power. To sharpen knives 24, a sharpening attachment or device 40 is provided which is mounted on top wall 16 and 55 operates through the opening 18. Device 40 comprises a guide track 41 having a pair of relatively spaced track members 42 and 44 which extend parallel to each other and parallel to the axis of cutter 20. Mounted on track 41 for reciprocable movement thereover, is a carriage 45 having members 46 which engage and slide 60 on the track members 42 and 44. Connected to carriage 45 is a handle 48 (FIG. 2) to facilitate manual reciprocation of the carriage over the track.

Carriage 45 has a tool holder 50 threaded therein 65 for adjustment about an axis transverse to the axis of the cutter 20 whereby the tool holder can be threaded toward the cutter. Tool holder 50 threadably supports a chuck member 51 in which an abrasive sharpening element 52 is mounted. The lower end 53 of the 70 sharpening element projects through the opening 18 and is engageable with the cutting edges 25 of the

knives 24. Cutter 20 rotates at a high r.p.m. and when the carriage 45 is reciprocated from one axial end of the track 41 to the opposite end thereof the sharpening element 52 moves across the cutting edges of all of the knives on the cutter to thereby sharpen them. When a sharpening action takes place, the lower end 53 of the sharpening element becomes worn and to compensate for such wear, the tool holder 50 is supported on the carriage 45 to be indexed downwardly relative thereto by means which will now be described.

As shown best in FIG. 2, when carriage 45 is in a retracted starting position, the sharpening element 52 is disposed at one axial end of the cutter 20. The upper end of the tool holder 50 has radially extending ratchet teeth 54 which form a ratchet wheel concentric with the axis of the tool holder and the sharpening element 52. Teeth 54 are engageable with a fixed pawl or detent 55 and a resilient holding pawl or detent 56. When the ratchet teeth 54 are brought into engagement with pawl 55, the tool holder 50 is rotated in the carriage 45 and the sharpening element 52 is indexed downwardly. Detent 56 provides means to prevent retrogressive rotation of the tool. The pawl 55 is fixedly disposed at one end of the guide track 41 and adjacent the track member 44. At the opposite end of the track 41, and thus the opposite axial end of the cutter 20, a pawl 58 is provided which is located adjacent the track member 42. At the outer end of a reciprocating stroke, the pawl 58 engages the ratchet teeth 54 and rotates the tool holder 50. A holding detent 59 is provided, the same as detent 56, to prevent the tool holder from reverse rotating.

Thus, the tool holder is adapted to be indexed downwardly at both ends of a reciprocating stroke. The axial half of the cutter 20 which is located adjacent the end of track 41 having the pawl 55, is sharpened primarily by engagement of the tool holder with the pawl 55. The other axial half of the cutter 20 is sharpened primarily by the downward indexing of the tool holder provided by the fixed pawl 58. Pawl 55 is so located and of such extent that tool holder 50 is rotated a distance of one ratchet tooth each time it engages the pawl when carriage 45 is retracted. Pawl 58 operates in the same manner to rotate the tool holder a distance of one ratchet tooth each time carriage 45 is extended. Thus cutter 20 is uniformly sharpened for its full axial length when carriage 45 is reciprocated. No oversharpening of one end of the cutter will result as happened heretofore, and no special handling of the sharpener is required by the operator.

While this invention has been described in connection with a particular embodiment thereof, it will be understood that it is capable of further modification, and this application is intended to cover any variations, uses, or adaptations following, in general, the principles of the invention and including such departures from the present disclosure as come within known or customary practice in the art to which the invention pertains, and as fall within the scope of the invention or the limits of the appended claim.

Having thus described our invention, what we claim is:

15 A device for sharpening a rotatable cutter of substantial axial length while it is rotating wherein the cutter has angularly spaced knives which on rotation of the cutter generate a cylinder, comprising a guide track, said guide track having first and second spaced track members extending parallel to each other and to the axis of said cutter, a carriage mounted on said track and reciprocable from one end to an opposite end thereof, said carriage when reciprocated traversing the full axial length of said cutter, a tool holder threadably supported on said carriage for adjustment between said track members and toward said cutter about an axis transverse to the direction of movement of said carriage, an abrasive sharpening element carried on said tool holder and engageable with said knives, a ratchet wheel fixedly mounted on said tool holder and coaxial therewith, said ratchet wheel having a plurality of ratchet teeth, a first pawl mounted adjacent said first track member and at said one end of said track, a second pawl mounted adjacent said second track member at said opposite end of said track, said ratchet wheel being engageable with said first pawl when retracted to said one end of said track and with said second pawl when moved to said other end of said track, said tool holder being rotated to index said sharpening element toward said cutter head responsive to each engagement of said ratchet wheel with said pawls, said pawls both operating to rotate said tool holder in the same direction and being similarly constructed whereby the amount of indexing of said sharpening element is the same at each end of said track.
